UNITED STATES PATENT OFFICE.

CLIFFORD H. FISHER, OF FORT LAUDERDALE, FLORIDA.

GARMENT HANGER.

Application filed May 8, 1925. Serial No. 28,910.

My invention relates to improvements in garment hangers.

An object of my invention is to provide a device for hanging trousers in an upright position instead of in an inverted position as is necessary with the hangers now generally used.

Another object of my invention is to provide a device, to accomplish the above objects, that may be mounted on a closet door or wall and may be swung against said door or wall.

Another object of my invention is to provide a device that is simple and economical of construction and operation for attaining the above objects.

These and other objects are attained by the means described herein and disclosed in the accompanying drawings, in which:

20 Fig. 1 is a side elevation of a device of my invention.

Fig. 2 is a top plan view of the device shown in Fig. 1.

25 Fig. 3 is an elevational view of a clothes pin or clamp forming a detail of my invention.

Fig. 4 is an elevational view of a modified form of a device embodying therein my invention.

30 Fig. 5 is an end elevation of a bracket used with the modified form shown in Fig. 4, forming a detail of my invention.

Fig. 6 is a front elevation of a group of hangers of the type disclosed in Fig. 1.

35 The hanger 10 of my invention comprises an arcuate body portion 11 having a clothes pin or clamp 12 secured to its front end 13. An extension or bracket 14 is formed at the other end 15 of the body 11. One member 40 16 of a hinge 17 is secured to the extension 14 by any suitable means, such as screws 18. The other member 19 of the hinge 17 is secured to the door or wall 20 of a cupboard or closet. The hinge 17 permits the hanger

45 10 to be swung next to and adjacent the said door or wall 20, as disclosed at 21 in Fig. 6.

50 The body 11 extends below the extension or bracket 14 thereby providing an arcuate ledge 22 over which the rear portion 23 of a pair of trousers or the like 24 is placed. The front portion 25 of the trousers 24 is received between the jaws 26 and 27 of the clothes pin or clamp 12. A spring 28 yieldingly 55 resists separation of the jaws 26 and 27 of the clamp 12 thereby retaining the trousers

24 in position. A screw 36 passes through the spring 28 and secures the clamp 12 to the front end 13 of the hanger 10. It should be observed from Fig. 1 that the trousers 60 are hung in an upright position, thereby obviating the necessity of removing the contents from the pockets before said trousers are placed on a hanger.

In the modified form of garment hanger 65 29 disclosed in Fig. 4, the extension 14 is dispensed with and a lug 30 is formed on the body portion 11. The lug 30 is provided with a perforation 31 for the reception of a screw or bolt 32. The bolt 32 is utilized 70 to secure the hanger 29 to a bracket 33, shown in Fig. 5, which bracket in turn is secured or fastened to a door or wall 34 or pedestal.

Fig. 6 illustrates how a multiplicity of 75 hangers 10 may be mounted on a panel 35, so as to form a group of hangers that can be readily secured or fastened to a wall or the like when more than one hanger is 80 desired.

Although I have shown and disclosed my garment hanger as one made of wood, it should be noted that the same may be made of wire or metal as well. Further, instead of using a detachable spring clamp or clothes pin 12, this clamp may be developed integral with the body of the hanger, at the end of said body, should the body be made of wire, or an eccentric clamp may be used in lieu of a spring clamp. Also a pedestal may 85 be employed to support a hanger instead of securing the hanger to a door or wall, all within the scope of my invention. It should also be noted that the hanger may be utilized for supporting garments other than 90 trousers such as knickerbockers, skirts, pants, etc.

95 What I claim is:

1. A trouser hanger comprising an arcuate body portion having a bracket formed thereon, an arcuate ledge extending from the body portion below the bracket over which the rear portion of a pair of trousers is placed, supporting means carried by the front end of the body portion for receiving the front portion of the trousers, the supporting means being in alignment with the ledge for tautly retaining the waist band of the trousers in a horizontal position, and a hinge secured to the bracket for hingedly mounting the hanger. 100

105 2. In a device of the class described the

combination of a body portion, an arcuate ledge extending from the body portion over which the rear portion of a garment is placed, and a garment supporting means secured to the front end of the body portion for receiving the front portion of a garment, the supporting means holding the garment

tautly drawn about the ledge thereby preventing the garment from disengagement with the hanger.

10

In testimony whereof, I have hereunto subscribed my name this 4th day of May, 1925.

CLIFFORD H. FISHER.
